UNITED STATES PATENT OFFICE.

HENRY WARD AND JOHN S. UTTER, OF STOCKTON, CALIFORNIA.

PIANO-FORTE MUSIC-RACK ILLUMINATOR.

SPECIFICATION forming part of Letters Patent No. 324,901, dated August 25, 1885.

Application filed January 10, 1885. (No model.)

To all whom it may concern:

Be it known that we, HENRY WARD and JOHN S. UTTER, citizens of the United States, residing at Stockton, in the county of San Joaquin and State of California, have invented 5 certain new and useful Improvements in Piano-Forte Music-Rack Illuminators, of which the following is a specification, reference being had therein to the accompanying drawings.

10 Figure 1 is a side elevation showing method of attachment to a square piano. Fig. 2 is a transverse section of the same. Fig. 3 is a side elevation of a portion, showing method of attachment to an upright piano. Fig. 4 is a 15 transverse section of Fig. 3. Fig. 5 is a top view of the supporting stem of Fig. 1.

Similar letters of reference indicate corresponding parts.

The principal object of our invention is to 20 provide means for illuminating the music-racks of piano-fortes by the use of such devices as may be readily attached to a piano.

The invention will first be described in connection with the drawings, and then pointed 25 out in the claim.

Let N represent the body of a square piano, to which is screwed a flange, H, having a neck, I, over which is inserted the rear collar, F, of a supporting-stem, E, the collar F being fixed 30 firmly in position by a thumb-screw, G, which screws into the top of the neck I of flange H. The stem E extends forwardly, and has at its forward end a collar, D, and reservoir or fountain A, for petroleum, having a neck, e, which screws onto a tube-piece, b, which is inserted 35 into collar D, and has at its top and just above collar D a threaded ring, c, screwed upon it, and is formed with a shoulder at each end, so that the ring c and neck e may screw up tightly 40 and still permit of a flexible joint. Into the ring c is screwed an elbow-tube, d, which

at its head screws into a threaded ring, f, which engages with a stem-tube, B, which screws at its upper end into a threaded ring, g, engaging with an elbow-tube, h, which has 45 a threaded ring, i, screwing upon its head and engaging with burner-tube C, having any desired style of globe-holder. The burner C is also provided with a cap, j, beneath which, around the edge of the burner, are perforations. Petroleum is supplied to the reservoir or fountain A, and a wick inserted, reaching therefrom to near the top of the tube C. The tube C is of thin material at its top, so that when means of ignition are supplied at the 50 perforations of its head the heat causes gas to be generated from the petroleum in the fountain A and connecting wick, which gas burns brightly and steadily and furnishes the means for illuminating the music-rack of the 55 instrument, and dispenses with the use of lamps, &c. To attach to an upright piano, the neck I is bent so that the flange H may be vertical and be attached to the instrument M, as shown in Figs. 3 and 4.

We are aware that some of the mechanism we have illustrated and described is not new; but,

What we claim as being of our invention is—

The illuminator consisting of the plate H, having the neck I and screw G, the stem E, having the collars F D, the reservoir A, the tube B, and the burner consisting of the perforated cap j, substantially as shown.

In testimony whereof we affix our signatures in presence of two witnesses.

HENRY WARD.
JOHN S. UTTER.
